UNITED STATES PATENT OFFICE

CORTICE H. HALL, OF GLEN ROCK, NEW JERSEY, ASSIGNOR TO DOMESTIC STOKER COMPANY, OF NEW YORK, N. Y., A CORPORATION OF DELAWARE

FURNACE

Application filed February 2, 1928. Serial No. 251,246.

The present invention relates to automatic furnaces and has for an object to provide an improved furnace having a plurality of burners adapted to be fed from a common fuel hopper.

The nature and objects of the invention will be better understood from a description of a particular embodiment thereof, for the purpose of which description reference should be had to the accompanying drawings forming a part hereof and in which—

Figure 1 is a side view of a duplex furnace constructed in accordance with the principles of the invention,

Figure 2 is a front view of the same showing the feed actuating mechanism,

Figure 3 is a detail plan view of the fire pots showing the position of the fuel feeding mechanism, and

Figure 4 is a sectional view of the same taken on the line IV—IV of Fig. 3.

The apparatus shown for the purpose of illustration comprises a fuel hopper 5, a pair of fire pots 6, 7 of the underfeed type and screw conveyors 8, 9 arranged to feed fuel from the hopper 5 to the respective fire pots together with a conveyor 10 for removing ashes from beneath both fire pots.

Preferably a motor 11 is arranged to automatically actuate the two fuel conveyors and the ash conveyor at an adjustable rate. As shown, a fan 13 is secured to the motor shaft to supply a forced draft through the conduit 14 to the casing 15 surrounding the conveyor screws which casing provides a flue for the forced draft.

The shafts of the screw conveyors 8, 9 and 10 carry respectively sprocket wheels 16, 17 and 18 connected thereto by suitable clutches as indicated at 20, 21 and 22 in Fig. 1. The ends of the shafts are square to receive a crank for operation by hand to dislodge material in case of need. The sprocket wheels are driven intermittently from the motor shaft by suitable mechanism. As shown, a sprocket chain 25 connects the three sprockets and the shaft of the conveyor 8 carries a ratchet wheel 26 intermittently driven by a pawl 27 carried by the rocking arm 28 which is rocked by a link 29 connected to the crank 30 which in

turn is driven by a worm and wheel 30' gearing from the motor shaft 12. A holding pawl 31 prevents backward movement of the ratchet wheel 26. The sprocket chain is tensioned by a spring pressed sprocket wheel 32. 55

In order that the extent of actuating movement of the ratchet wheel 26 may be varied, an adjustable shield 33 is pivoted on the shaft of the screw 8 and a link 34 operatively connects the same to a collar 35 adjustably mounted on the shaft of the conveyor 9 and having a projecting handle 36 to facilitate adjustment thereof. A suitable scale 38 and pointer 39 indicate the position of adjustment of the handle 36 and cam 33 and therefore the 60 rate of feed.

The two fire pots are positioned relatively close together, the distance between the center lines thereof being less than the outside diameter of the burner plate of either fire pot. 70 The fire pots are arranged at different distances from the hopper in order that the conveyors for feeding fuel thereto may lie relatively close together as best shown in Fig. 3. Each fire pot is made up of upper and lower 75 sections; the upper sections 40 are six in number and all are similar. The lower sections 41 and 42 are of two different shapes and five in number. The sections 42 are formed to extend substantially vertical to a greater 80 height than the sections 41 in order to compensate for the tendency of the feed screw to feed the fuel more to the side of the furnace toward which its upper portion turns. The sections 40 are surrounded by an inner 85 annular supporting plate 44 and an outer perforated burner plate 45. The series of perforations 46 of the burner plates 45 extend around the plates except at the portions where said plates join each other as best indicated in Fig. 3. 90

The foregoing description of a particular embodiment is illustrative merely and not intended as defining the limits of the invention.

I claim:

1. A duplex furnace comprising a fuel hopper, a pair of underfeed firepots at different distances from said hopper and closely adjacent each other, a pair of parallel screw conveyors of different lengths arranged to 100

feed fuel from said hopper to said firepots, said firepots being arranged on the same level, one diagonally behind the other and the conveyors being arranged on the same level and closely adjacent side by side to feed equally

5 from said hopper, a conveyor mechanism for removing ashes from beneath both firepots comprising a screw conveyor extending parallel to said first mentioned screw conveyors and an actuating mechanism for the three

10 screw conveyors comprising sprocket wheels secured to the respective conveyors, a sprocket chain engaging the three sprocket wheels, a ratchet wheel secured to one of said sprocket wheels, a motor, means driven by said motor

15 and comprising a pawl arranged intermittently to actuate said ratchet wheel, an adjustable shield arranged to engage said pawl to make the same inoperative during a portion of its reciprocating movement and means

20 for adjusting said shield, substantially as described.

2. A duplex furnace comprising a fuel hopper, a pair of underfeed firepots at different distances from said hopper and closely

25 adjacent each other, a pair of parallel screw conveyors of different lengths arranged to feed fuel from said hopper to said firepots, said firepots being arranged on the same level, one diagonally behind the other and the conveyors being arranged on the same level and closely adjacent side by side to feed equally

30 from said hopper, a conveyor mechanism for removing ashes from beneath both firepots comprising a screw conveyor extending

35 parallel to said first mentioned screw conveyors and an actuating mechanism for the three screw conveyors comprising sprocket wheels secured to the respective conveyors, a sprocket chain engaging the three sprocket

40 wheels and means for actuating said sprocket chain.

In testimony whereof, I have signed my name to this specification this 17th day of January, 1928.

45

C. H. HALL.
